UNITED STATES PATENT OFFICE.

GEORGE E. TARNOW, OF CHICAGO, ILLINOIS.

BOW-HOLDER.

1,313,137.

Specification of Letters Patent.

Patented Aug. 12, 1919.

Application filed April 17, 1919. Serial No. 290,796.

To all whom it may concern:

Be it known that I, GEORGE E. TARNOW, a citizen of the United States, residing at Chicago, county of Cook, State of Illinois, 5 have invented a certain new and useful Improvement in Bow-Holders, and declare the following to be a full, clear, and exact description of the same, such as will enable others skilled in the art to which it pertains 10 to make and use the same, reference being had to the accompanying drawings, which form a part of this specification.

My invention has for its object to produce a simple and novel pin or clasp for 15 holding a ribbon bow or other ornament.

The device is of the kind comprising a body member carrying on its under side a suitable pin for attaching it to the hair or clothing of the wearer and on the other side 20 a clasp in the form of a suitable bowed strip or band between which and the body member the ornament is to be held. All similar devices of which I am aware are open either to the objection that they will not stay 25 locked or closed or to the objection that it is difficult to manipulate them in opening and closing the clasp part. Specifically considered, the present invention has to do with the catch or locking means for holding the 30 free end of the clasp or band to the body member and, viewed in its most specific aspect, the present invention may be regarded as having for its object to produce a catch construction which may be manipulated 35 easily to open or close the clasp and, when closed, will guard against accidental unlocking.

The various features of novelty whereby 40 my invention is characterized will herein- 45 after be pointed out with particularity in the claims; but, for a full understanding of my invention and of its objects and advantages, reference may be had to the following detailed description taken in connection with 50 the accompanying drawing, wherein:

Figure 1 is a plan view of a device arranged in accordance with the preferred embodiment of my invention, showing the clasp closed;

Fig. 2 is a view similar to Fig. 1, the clasp being thrown back or open; and

Fig. 3 is a section taken approximately on line 3—3 of Fig. 1.

In the drawing, 1 represents a small flat 55 piece of metal having on one side a suitable pin device, 2. On the other side is an arched

band or strip, 3, firmly connected at one end to one of the long edges of the body member, at about the middle of the latter, by means of a long strong hinge, 4. At the opposite 60 edge of the body member, directly across from the hinge is an up-turned ear or projection, 5, the free end of which is turned inwardly and downwardly to form a hook, 6. Close to the hook is an upwardly-projecting tongue or guard, 7, which may conveniently be formed by striking up a small piece of metal out of the body member as shown. The member 3 is provided near its free end with a hole or slot, 8, which is 70 adapted to receive the hook 6; the guard being located just far enough away from the hook to permit the free end of the member 3 to be moved up and down through the intervening space.

When a bow or other ornament is to be secured in the holder, the guard acts to leave open a clear passage for the free end of the clasp member in approaching the hook serving, in fact, as a guide to direct the end 80 of the clasp properly down in front of the hook. The clasp is preferably made of material which is more or less springy and therefore, as soon as the opening has been carried down far enough to register with 85 the hook, the clasp automatically interlocks itself with the hook. If, for any reason, the clasp is subjected to pressure from without tending to push it off the hook, the guard 90 will serve as a stop to prevent accidental disengagement. However, when it is desired to unfasten the clasp a gentle pressure tending to sharpen the curvature of the arch 95 will carry the free end of the clasp against the guard and in such relation thereto and to the hook that it may be raised without being interfered with by the hook.

While I have illustrated and described with particularity only a single preferred form of my invention, I do not desire to be 100 limited to the exact structural details thus illustrated and described; but intend to cover all forms and arrangements which come within the terms employed in the definitions of my invention constituting the appended 105 claims.

I claim:

1. A device of the character described comprising a plate having thereon a fastening device, an arched clasp hinged at one 110 end to one edge of the plate and extending across to the opposite edge, said plate having

at the latter edge an inwardly-directed hook and a guard lying on the inner side of the hook, and said clasp having at its free end an opening therein adapted to receive the hook.

5 2. A device of the character described comprising a plate having thereon a fastening device, an arched clasp hinged at one end to one edge of the plate and extending 10 across to the opposite edge, said plate hav-

ing in the vicinity of the opposite edge two up-turned ears one of which is closer to the said hinge than the other, the outer ear having its upper end extending inwardly and downwardly to form a hook, and said clasp 15 having in its free end a slot or hole adapted to receive said hook.

In testimony whereof I sign this specification.

GEORGE E. TARNOW.

Copies of this patent may be obtained for five cents each, by addressing the "Commissioner of Patents, Washington, D. C."
